FLIER CONSTRUCTION

Michael J. McHale, Scranton, Pa.

Application September 14, 1949, Serial No. 115,641

10 Claims. (Cl. 57—116)

1

My invention relates to fliers of the type used with spinning machines, and more particularly to a novel flier block arrangement having improved means for attaching and supporting the flier wire and the flier wire balance.

Conventional flier blocks are generally adapted for use with either single or double armed flier wires. In the use of wires which are symmetrically arranged with respect to the block, that is to say, when the arms of the wires extend outwardly on opposite sides of the flier block, the flier remains in a substantially uniformly balanced condition during its rotation about the bobbin spindle. Under certain winding conditions it is desirable to use a single flier wire having the arms thereof projecting from the same side of the block. It will be appreciated that in the use of wires arranged in this manner, that means must be provided to balance the flier and more particularly to overcome the unbalanced forces set up by the wires when the block is rotated.

Heretofore it has been proposed to provide fliers comprising a plurality of separate parts or elements constructed and arranged to inter-lock whereby to form a complete flier. It has also been proposed to effect balancing by attaching a member in the form of a wire loop, or other bail-like device to the block on the side opposite the flier wires. In Patent 2,187,862, for example, issued to me on January 23, 1940, there is disclosed a flier construction having a flier wire support member in the form of a plate adapted to fit over the head portion of the flier body or block, the plates being attached to the flier body by means of a cap positioned below the plate and attached thereto by spot welding; also in Patent 2,259,826, issued to me October 21, 1941, there is disclosed a flier construction wherein the block is designed to receive a balancing member, arranged to compensate the unbalanced forces due to projection of the flier wire arms on the same side of the block.

The present invention relates to a flier of the general type disclosed in the aforementioned patents, and more particularly to a counterpoised flier block with a single flier wire and a counterbalance therefor. After considerable research and experimentation, I have found that the flier constructions of the type disclosed in my prior patents, and other constructions exemplified by prior art arrangements comprising multi-part blocks, can be substantially simplified to provide improved operation with marked economies in manufacture.

2

An object of my invention is to provide an improved flier construction having a substantially flat, counterpoised body section, a detachable flier wire, and a detachable flier wire balance.

Another object of my invention is to provide a flier construction having improved means for attaching and supporting a flier wire thereon.

Yet another object of my invention is to provide an improved flier wire balance.

10 Still another object of my invention is to provide a flier wire balance which may be quickly attached to or removed from a flier block.

15 A further object of my invention is to provide a detachable flier wire balance which can be applied to or removed from a flier block without the use of special tools or implements.

20 Yet another object of my invention is the provision of a counterpoised, flat flier mounting a single flier wire, and held in operative position on a capped bobbin spindle by a superposed weight.

25 It is also an object of my invention to provide improved flier wire balances which are self-seating and self-locking.

20 With these and other objects in view, which may be incident to my improvements, the invention consists in the parts and combinations to be hereinafter set forth and claimed, with the understanding that the several necessary elements, comprising my invention, may be varied in construction, proportions and arrangements, without departing from the spirit and scope of the appended claims.

35 In order to make my invention more clearly understood, I have shown in the accompanying drawings means for carrying the same into practical effect, without limiting the improvements in their useful applications to the particular constructions, which for the purpose of explanation, have been made the subject of illustration.

40 In the drawings:

Figure 1 is an elevational view, partly in section, showing a flier equipped with my improved balance, in the operative position on a bobbin spindle.

Fig. 2 is a plan view of the flier shown in Fig. 1;

Fig. 3 is a perspective elevated view of one form of the balance member;

Fig. 4 is a view similar to Fig. 2, and showing a modified form of flier balance;

Fig. 5 is a perspective elevated view of the modified form of flier balance shown in Fig. 4;

Fig. 6 is a perspective view of the top of a bob-

bin, showing a flat counterpoised fier body of plastic, or the like, having a unilateral arm and weighted in place on the spindle, the spindle being capped;

Fig. 7 is a perspective view of the plastic fier shown in Fig. 6; and

Fig. 8 is a view showing a flat metal fier body similar to the construction shown in Fig. 7.

The proposed form of fier construction of the present invention, comprises essentially, a generally flat, fier block, in the form of a centrally apertured body member having diametrically opposed fier wire support members and fier wire balance support, said supports being substantially counterpoised. The fier wire support comprises a transversely apertured lug offset from the head portion and an aligned hook member mounted adjacent the periphery of the fier. The counterpoised section of the fier body comprises a generally rectangular thickened body portion, the top surface of which is slotted or apertured to receive the spring-biased arms of a generally rectangular fier wire balance. In assembling the fier, the fier wire balance is snapped in position, and the fier wire is locked in place, after which the fier is inserted over the spindle with the eccentric foot positioned in locking engagement in the ferrule of the bobbin.

Referring to the drawings, and more particularly Fig. 1, there is shown a fier arrangement associated with a bobbin 1, mounted in operative position on a suitable spindle 2, of a conventional winding machine. The bobbin is provided with a head member 3, and a centrally recessed portion 4, adapted to receive a ferrule 5, having an aperture 6 through which the fier foot of the block 8 is inserted. The fier block 8 comprises an upper body section 9, and a depending tubular section 10, provided with the foot 7, as previously described. The body and tubular sections are provided with a central aperture 11, desirably tapered, and adapted to fit over the spindle 2 of the bobbin. The body section is also provided with an offset lug 12, having a transverse aperture 13. The fier body includes a depressed lateral platform section 14, tapering toward the edge and thickened on the under side, as indicated at 15. Adjacent the edge 15, there is provided an angular locking lug 15' adapted to receive the section 21 of the fier wire in locking engagement. Diametrically opposed to the platform 14 is the generally rectangular, counterpoised section 16, having its central body section 9 provided with a depressed offset section 17, forming a platform 18 for the fier wire balance. The section 16 is provided with spaced, parallel undercut slots 19, joined by a transverse slot 20, forming a seat for the ends of the fier wire balance.

The fier wire 20 comprises a straight body section 21, having its forward end 22 bent at right angles, and terminating in the thread-receiving loop 23. The rear end of the fier wire is laterally offset at a slight angle as shown at 24, and is bent on itself to form a horizontal cross bar 25, having its end 26 bent at a slight angle. The fier wire is mounted in place by inserting the transverse leg section 25 through the aperture 13 in lug 12, and springing the section 21 laterally to clear the locking lug 15', the section 21 of the fier wire being slipped in place under the locking lug, and spring-biased therein in locked position.

The fier wire balance 30 is of generally rectangular shape, and comprises a pair of spaced

parallel arms 31, 32, joined by cross bar section 33. The forward ends of the legs 32 are bent inwardly, as shown at 34, 35, and then forwardly, as shown at 36, 37, the ends 38, 39, being bent inwardly at right angles. As shown in Fig. 3, the member 30 and the legs 31, 32, are normally spring-biased to flare outwardly in the unrestrained, inoperative position. In the operative position, as shown in Fig. 2, the legs 31, 32 are apposed, and the segments 36, 37, are fitted in the undercut slots 19, with the ends 38, 39 fitted in the transverse slot 20, whereby when the pressure is released, the spring-bias of the legs 31, 32, positively seats the locking sections 36, 37, and 38, 39 in their respective seats.

In the form shown in Figs. 4 and 5, the fier is provided with a pair of spaced, transverse apertures 41, 42, adapted to receive the locking members of the modified fier wire balance 40, which will now be described. The member 40 comprises spaced, parallel arms 43, 44, joined by cross bar section 45, and terminating in inturned end portions 46, 47 which are generally parallel to section 45, and are mutually displaced by an amount equivalent to the spacing between the apertures 41, 42 in the fier block. Referring more particularly to Fig. 5, it will be seen that in the unrestrained position, the legs 43, 44 are spring-biased inwardly toward each other. When the member 40 is mounted in place on the fier block, the legs 43, 44 are sprung apart and the end sections 46, 47 are inserted in the apertures 41, 42, being locked therein by the spring-bias of the unit.

It will be seen that the fier wire balance 30, shown in Figs. 1, 2 and 3, is maintained in substantially rigid position, while in the form shown in Figs. 4 and 5, the member 40 may be displaced upwardly, under applied pressure, but will spring back into its normal, flat, seated position when the biasing pressure is released.

In Fig. 6 there is shown a plastic fier body 50 for use with large bobbins. In this form of the invention, a bobbin 60, having a head portion 61, is mounted on an oversize spindle 62, which is provided with a millnut 63 at the top thereof. The plastic fier body 50 is comprised of a generally flat body portion 51, having a tapered forward end 52, slightly thickened as shown at 53, a generally rectangular rear platform section 54, having a slightly thickened portion 55. A centrally apertured ring section 56 surmounts the top of the fier body, and is provided with a forward, transversely apertured lug 57, corresponding to member 12 of the other fier bodies, and a locking finger 58, corresponding to member 15'. It will be noted that in this construction, the fier wire 20 is locked in place in the usual manner, but is not counterbalanced. An annular weight 64 is fitted over the spindle 62 and rests on the upper surface of section 56 of the fier body. The millnut 63 restrains the weight 64 from any upward movement sufficient to permit it to ride up and off of the top of the spindle.

In Fig. 8, there is shown a metal fier body 70, having the usual generally flat body section 71, a tapering forward section 72, formed with depending thickened section 73, a rectangular rear platform section 74, having a depending thickened section 75. The centrally apertured collar 76 has an opening of a diameter corresponding to the openings 11 of the fliers of Figs. 1, 2 and 4. A transversely apertured lug 77 is formed on the forward side of member 76 and

cooperates with locking finger 18 to hold the flier wire 20 in locked relation.

It will be seen that with the improvements of the present invention, when a single flier wire is used, the loops 30 and 40, serving as flier wire balancing members, will balance out the centrifugal forces generated by the flier wire when the flier block is rotated, thus providing uniform tension on the yarn. Similarly, by the use of weight 64, the desired tension or drag on the yarn can be obtained.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention, or exceeding the scope of the appended claims.

What is claimed is:

1. A flier block construction for spinning machines and the like, comprising a centrally apertured, generally flat body member having a thickened portion on the top surface thereof, said portion forming a continuation of the central aperture in the body member; one side of said body being tapered and the other side substantially rectilinear; flat bearing surfaces formed on the bottom of the flier at both ends thereof; and flier wire locking and supporting means comprising a pair of cooperating members, one of said members being formed integral with the upper surface of the tapered side of the flier body in the vicinity of the end thereof, the second said member being integral with the thickened portion of the body member.

2. A flier block construction for spinning machines and the like, comprising a centrally apertured, generally flat body member having a thickened portion on the top surface thereof, said portion forming a continuation of the central aperture in the body member; one side of said body being tapered and the other side substantially rectilinear; flat bearing surfaces formed on the bottom of the flier at both ends thereof; and flier wire locking and supporting means formed integral with the upper surface of the tapered side of the flier body and comprising an inverted L-shaped hook adjacent the end thereof, and a wire-receiving loop integral with the thickened portion of the body member.

3. A flier block construction for spinning machines and the like, comprising a centrally apertured, generally flat body member having a thickened portion on the top surface thereof, said portion forming a continuation of the central aperture in the body member; one side of said body being tapered and the other side substantially rectilinear; flat bearing surfaces formed on the bottom of the flier at both ends thereof; and flier wire locking and supporting means formed integral with the upper surface of the tapered side of the flier body and comprising a radially disposed, inverted L-shaped hook adjacent the outer edge thereof, and a transversely disposed wire-receiving loop integral with the thickened portion of the body member.

4. A flier block construction for spinning machines and the like, comprising a centrally apertured, generally flat body member having a thickened portion on the top surface thereof, said portion forming a continuation of the central aperture in the body member; one side of said body being tapered and the other side sub-

stantially rectilinear; flat bearing surfaces formed on the bottom of the flier at both ends thereof; flier wire locking and supporting means formed integral with the upper surface of the tapered side of the flier body and comprising a radially disposed inverted L-shaped hook adjacent the end thereof, a transversely disposed wire-receiving loop integral with the thickened portion of the body member, and a flier wire detachably secured in place on the flier body by said wire-receiving loop and inverted L-shaped hook.

5. A flier wire mounting means for flier bodies, comprising a flier body having a thickened central portion apertured to receive a spindle, a flier wire supporting arm and means associated with the thickened portion and said flier wire supporting arm to detachably receive and lock a flier wire, said means comprising a transverse aperture formed on the flier arm side of the thickened portion, and a radially aligned hook adjacent the end of said flier arm support, and a flier wire secured in place on said flier arm, said flier wire having a generally straight body portion with a reversely bent angular rear portion extending through the transverse aperture in said thickened portion and spring-biased in locking engagement in and under said hook, whereby the flier wire is locked under operative conditions and is manually detachable by unseating the wire from under the hook, and sliding the rear end out of engagement with the wire-receiving aperture in the thickened portion of the flier body.

6. A flier block construction for spinning machines and the like, comprising a generally rectilinear flat body portion with a unilateral tapered platform of reduced thickness; coplanar, flat bearing surfaces formed on the bottom of the flier at both ends thereof; a depending collar extending from the bottom of the block, said collar having an off-set foot formed thereon, adapted for insertion into the head of a bobbin, a spindle-receiving aperture extending through the block body and depending collar and dividing the flier block into an elongated flier wire supporting platform and a shorter, thickened body portion; and flier wire locking and supporting means comprising a pair of cooperating members, one of said members being formed integral with the upper surface of the tapered side of the flier body in the vicinity of the end thereof, the second said member being integral with the said thickened body.

7. A flier block construction for spinning machines and the like, comprising a generally rectilinear flat body portion with a unilateral tapered platform of reduced thickness; coplanar, flat bearing surfaces formed on the bottom of the flier at both ends thereof; a depending collar extending from the bottom of the block, said collar having an off-set foot formed thereon, adapted for insertion into the head of a bobbin, a spindle-receiving aperture extending through the block body and depending collar and dividing the flier block into an elongated flier wire supporting platform, and a shorter, thickened body portion; and flier wire locking and supporting means formed integral with the upper surface of the tapered side of the flier body and comprising an inverted L-shaped hook adjacent the end thereof, and a wire-receiving loop integral with the said thickened body.

8. A flier block construction for spinning machines and the like, comprising a thickened, generally rectilinear, flat body portion at one end of

the block, and a thinner flier wire supporting tapering platform at the other end thereof; coplanar flat bearing surfaces on the bottom of the block at the ends thereof; a depending footed collar integral with the body of the block; a spindle-receiving aperture in said collar and block, said aperture being laterally off-set from the longitudinal center of the block toward the body end; flier wire securing means on said platform, and flier wire balance securing means at the thickened end of the block.

9. A flier block construction for spinning machines and the like, comprising a thickened, generally rectilinear, flat body portion at one end of the block, and a thinner flier wire supporting tapering platform at the other end thereof; coplanar flat bearing surfaces on the bottom of the block at the ends thereof; a depending footed collar integral with the body of the block; a spindle-receiving aperture in said collar and block, said aperture being laterally off-set from the longitudinal center of the block toward the body end; a flier wire detachably secured to said platform, and a flier wire balance member detachably secured to the thickened end of the block.

10. A flier block construction for spinning machines and the like, comprising a thickened, gen-

erally rectilinear, flat body portion at one end of the block, and a thinner flier wire supporting tapering platform at the other end thereof; coplanar flat bearing surfaces on the bottom of the block at the ends thereof; a depending footed collar integral with the body of the block; a spindle-receiving aperture in said collar and block, said aperture being laterally off-set from the longitudinal center of the block toward the body end; flier wire securing means formed integral with the upper surface of the platform comprising an inverted L-shaped hook adjacent the end of the platform and a flier wire securing loop formed on the inner end of the thickened body, a flier wire secured to the platform, and a flier wire balance secured to the thickened end of the block.
